SWEEPER

Ronald Clement Evans, Elgin, Ill., assignor to Elgin Sweeper Company, Elgin, Ill., a corporation of Illinois

Application March 18, 1938, Serial No. 196,635

6 Claims. (Cl. 15—85)

This invention relates to street or floor sweeping apparatus, and more particularly to the dirt collecting means thereof.

Many problems are encountered in the design of street or floor sweeping apparatus. The many and varied elements of the apparatus must all effectively cooperate with each other, each performing its individual function efficiently to bring about a satisfactory machine. The most efficient sweeping brush may be rendered unsatisfactory by an inefficient collecting and storage means for receiving and transposing the swept up debris and dirt.

It is thus an object of this invention to provide novel means for receiving and transposing dirt and debris as it is swept up by a sweeping brush and depositing the same in the interior of a storage hopper.

Another object of this invention is to provide novel means for preventing undesired accumulations of dirt and debris on the pick-up plate of the apparatus.

A further object of this invention is to provide a novel sweeping apparatus in which the dirt collecting pan or hopper is periodically oscillated or vibrated.

A still further object of this invention is to provide a novel sweeping apparatus in which the dirt collecting pan or hopper is provided with a pick-up plate or flippers which is periodically oscillated or flipped upwardly to prevent an accumulation of dirt and debris thereon and to effect a transposition of the dirt and debris into the dirt collecting pan or hopper.

Another and further object of my invention is to provide a novel means for periodically oscillating the dirt collecting pan or the pick-up plate of a street sweeping apparatus.

Another and still further object of this invention is to provide a novel improvement in street sweeping apparatus and the like which is economical to manufacture, and which is rugged and reliable in use.

The novel features which I believe to be characteristic of my invention are set forth with particularity in the appended claims. My invention itself, however, both as to its construction and its particular organization, together with further objects and advantages thereof, may best be understood by reference to the following description taken in connection with the accompanying drawings in which:

Figure 1 is an elevational view of a street sweeping apparatus;

Figure 2 is an enlarged elevational view of the

central portion of the apparatus illustrated in Figure 1 but with certain elements removed for the purpose of illustrating the hopper, the pick-up plate and the means for periodically oscillating the pick-up plate to effect a transposition of dirt and other debris from the pick-up plate to the hopper;

Figure 3 is a cross-sectional fragmentary end view of the apparatus taken along the lines III—III of Figure 2;

Figure 4 is a fragmentary plan view, partly in cross-section, taken along the line IV—IV of Figure 2; and

Figure 5 is an elevational view of a modified form of my invention in which the hopper itself is periodically oscillated to effect a transposition of dirt and debris from its pick-up edge to the opposite end of the hopper.

The street sweeping apparatus illustrated in Figure 1 of the drawings is mounted on a motor driven vehicle 10, the principal elements of the sweeping apparatus being a rotary broom or brush 11 and a dirt collector pan or hopper and their associated operating mechanism.

Although the structural form of the vehicle upon which the sweeping apparatus is mounted may vary within wide limits without departing from the spirit and scope of the present invention, vehicle 10 has been illustrated as a three wheel chassis having two front wheels 13 and a single pivotally mounted rear wheel 14. Front wheels 13 are the driving wheels of the vehicle 10 and are mounted on an axle 15 which is carried by axle support plates 16. The single rear wheel 14 is mounted on an axle 17 in a yoke assembly 18 which is pivotally mounted at the rear of the vehicle 10 for steering the same.

The motor from which power is derived to propel the vehicle and to operate the sweeping apparatus carried thereby may be of any suitable type, such, for example, as a gasoline motor. This motor is illustrated diagrammatically in the drawings by showing the motor hood 19 at the rear of the chassis 10 and the usual vehicle radiator 20. Power from the motor is transmitted through a pair of drive shafts mounted within the drive shaft housings 21 to bevel gear power take offs 22. A chain drive 23 from each power take off 22 to the front wheels 13 is provided in a manner well known to those skilled in the art.

Steering of the vehicle 10 is obtained by centrally mounting a steering wheel 24 which is mechanically connected to the pivotally mounted yoke assembly 18. Mounted on the vehicle 10

immediately behind the steering wheel 24 is a driver's or operator's seat 25.

The sweeping apparatus mounted on chassis 10 includes a rotary broom or brush 11, which sweeps the streets by lifting the dirt and light debris thereoff. Brush 11 is mounted in suitable bearings 26 carried at the lower ends of a pair of broom arms 27, the broom arms 27 being pivotally mounted on supporting brackets 28 extending from the underside of chassis 10. A flexible cable or chain 29 connected at one end to the lower end of the arm 27 and at the other end to the chassis 10 limits the extent to which the brush 11 may be lowered.

16 A second flexible chain or cable 30 is connected to one of the arms 27 as at 31, passed over a suitable sheave 32, and is then fastened at its upper end to the lower end 33 of a broom control lever 34. The lower end 33 of the broom control lever 34 is formed substantially in the shape of a quadrant of a circle. The ends of the flexible chain or cable 30 being connected to this quadrant at a point remote from the sheave 32. The outer curved edge of the quadrant 33 is channeled to permit the chain 30 to ride therein. As will readily be understood from a cursory inspection of Figure 1 of the drawings, movement of the control lever 34 toward the operator effects a raising of the brush 11 from the street which it is sweeping, and movement away from the operator lowers the brush 11.

The brush per se and the means for driving it form no part of the present invention. As illustrated in the drawings, the brush 11 is driven from the motor of the vehicle 10 in a suitable manner, such as by means of a chain drive 35, it being understood that the movement of the brush 11 is counterclockwise as viewed in Figures 1 and 2 of the drawings.

40 Counterclockwise rotation of the brush 11 as viewed in Figures 1 and 2 of the drawings throws the dirt and other debris on the street forwardly and upwardly. The dirt collecting pan or hopper 12 is mounted and arranged to catch the dirt and debris as it is thrown up by the brush 11. Two supporting arms or brackets 36 mounted on opposite sides of chassis 10 and extending downwardly therefrom provide the desired supporting structure for the hopper 12. The brackets 36 are formed with a principal downwardly extending portion 37 and a lower obliquely forwardly extending portion 38. The hopper 12 is pivotally mounted to the lower end of the brackets 36 as at 39, and is designed to move from the full line position in Figure 2 to the dotted line position in Figure 2 under certain circumstances presently to be described.

Hinged to the lower rear edge of the hopper 12 is a movable pick-up plate 40 having side walls 60 40' which telescope with the side walls of hopper 12. The pick-up plate 40 is rigidly secured to a hinge rod 41 which is rotatably mounted along the lower rear edge of the hopper 12. While during normal operation of the sweeping apparatus, dirt and other debris is thrown by the rotating brush 11 into the hopper 12, there is a tendency for the dirt and debris to accumulate on the pick-up plate, the pick-up plate 40 being designed to catch dirt and debris which is not thrown far enough by the brush 11 to reach the hopper 12. As will readily be apparent to those skilled in the art, if this dirt and debris which accumulates on the pick-up plate is not transposed to the interior of the hopper 12, the sweeping action of the apparatus will soon be-

come ineffective. It is, therefore, highly desirable that some means be provided for transposing the dirt and debris which accumulates on the pick-up plate 40 into the interior of the hopper 12. Such a means is provided in the structure described herein by periodically oscillating the pick-up plate 40 to effect a quick upward movement or flip of the pick-up plate 40.

The novel means by which the pick-up plate 40 is periodically oscillated will now be described. 10 The hinge rod 41 to which the pick-up plate 40 is rigidly secured, is provided with a crank arm 42. This crank arm 42 is connected to an actuating arm 43 by a slot and pin connection 44 and 15 45' respectively. The actuating rod 43 is carried on one side of the hopper 12 by two suitable supporting brackets 44, the brackets 44 being designed and arranged to permit limited longitudinal movement of the actuating rod 43 therein. A helical compression spring 45 surrounding the 20 actuating rod 43 extends between the rear bracket 44 and a stop pin 46 carried on the actuating rod 43. This compression spring 45 biases the pick-up plate to its lowermost position, a second stop pin 47 at the forward end of the actuating rod 43 being provided to limit the rearward movement of the actuating rod 43 and hence the downward movement of the pick-up plate 40.

The cam mechanism which provides the periodic actuation of the pick-up plate 40 includes 30 a rotating cam 48, which is preferably of the wiper or involute type such as is illustrated in Figure 2 of the drawings, and a roller bar 49 mounted on the actuating rod 43. The cam 48 is secured to a stub shaft 50 which is journaled 35 in a suitable bearing or aperture 51 located at an intermediate portion of one of the supporting brackets 36. Sprocket gear 52 (see Figure 4) is also secured to the stub shaft 50 which is journaled in a suitable bearing or aperture 51 located at an intermediate portion of one of the supporting brackets 36. Sprocket gear 52 (see Figure 4) is also secured to the stub shaft 50, a key 53 being provided to prevent movement of the sprocket gear 52 and the cam 48 on the shaft 40 50. A chain drive 54 connects the sprocket wheel 52 of the cam mechanism to the power take-off 22 as at 55 during forward movement of the vehicle, it being understood that the connection is such that counterclockwise rotation of the cam 50 48 is obtained during such forward movement of the vehicle.

As will readily be apparent from a close inspection of the various figures of the drawings, the cam 48 moves the actuating rod 43 to the right during a small fraction of each revolution of the stub shaft 50. This particular type of cam action is well known in the art and for that reason will not be described in further detail. It is apparent that when this type of cam action is 60 employed, the pick up plate 40 is given a quick upward movement during a fractional portion of each revolution of the sprocket wheel 52. During the remaining period of each revolution the pick-up plate 40 is held in its lower position by the biasing spring 45. This periodic upward movement of the pick-up plate 40 prevents an accumulation of dirt and other debris on the pick-up plate and effects a transposition of such dirt and debris to the interior of the hopper 12.

Means must, of course, be provided for dumping the dirt and debris from the hopper 12 after it becomes full. Such means may be conveniently provided by hinging the front end 56 of hopper 12 at the top as at 57. A flexible chain or cable 75

58 is connected to the hopper 12 as at 59 and is then passed over a sheave 60 and connected to the lower end of a dumping lever 61, the lower end 62 of the dumping lever 61 being formed in a manner similar to the lower end 33 of the broom lever 34. When the dumping lever 61 is in the position shown in Figures 1 and 2 of the drawings, the hopper 12 is in its normal operating position. When the lever 61 is moved to the right, as viewed in the drawings, the flexible cable or chain 58 lifts the hopper 12 upwardly about the pivot point 39. This upward movement of the left side of the hopper 12 effects an opening of the end wall 56 due to gravity and the dirt and debris falls out. After the sweeping apparatus has been removed from the point at which the dirt and debris was dumped, the hopper 12 is lowered by moving the dumping lever 61 back to its position as shown in Figures 1 and 2. The end wall 56 then closes automatically due to its own gravity pull and remains closed so long as the hopper 12 is maintained in its normal operating position.

In Figure 5 of the drawings, I have illustrated a modified form of my invention in which the hopper itself of the sweeping apparatus is periodically oscillated rather than periodically oscillating the pick-up plate. Referring now to Figure 5 of the drawings, a hopper 63 is provided which is pivotally supported from the chassis 10 of the sweeping apparatus by means of a pair of support brackets 64. Support brackets 64 are somewhat similar to the support brackets 36 in the preferred embodiment of the present invention with the exception that the lower ends 65 of the brackets 64 extend slightly rearwardly rather than forwardly. The hopper 63 is journaled in suitable bearings or apertures 66 at the lower end of the end portion 65 of brackets 64 by means of a hinge or supporting rod 67 which is rigidly secured thereto. A crank arm 68 is also tightly secured to the supporting rod 67 and carries a roller bar 69 at its upper end for engagement with a rotatable cam 70. Cam 70 is mounted on one of the supporting brackets 64 in a manner similar to that described in connection with the preferred embodiment of the invention and is connected by a chain drive (not shown) as was also described in connection with the preferred embodiment of the invention. As will readily be understood from an inspection of Figure 5 of the drawings, the hopper 63 is periodically oscillated from the full line position as shown in Figure 5 to the dotted line position as shown therein by virtue of engagement of the cam 70 with the roller bar 69 on crank arm 68. The end wall 71 of the hopper 63 is hinged at its top as at 72 and is provided at its lower end with a latch 73 to prevent an opening of the end wall during the operation of the hopper 63.

The periodic actuation or oscillation of the hopper 63 prevents an accumulation of dirt and debris along the rear edge of the hopper opposite the brush of the sweeping apparatus and effects a transposition of the dirt and debris to a central position or opposite end of the hopper. It will thus be understood that the present invention provides a simple and efficient way of preventing undesired accumulation of dirt and debris along the edge of the hopper which is disposed adjacent the rotary broom of a street sweeping apparatus.

The dirt and debris may be dumped from hopper 63 by releasing latch 73 and actuating the cam mechanism as for normal operation or a

suitable dump lever and chain as in Figure 2 may be provided.

Although I have shown and referred to my preferred embodiment as being of a size suitable for sweeping streets, it is to be understood that the invention is particularly well suited for use in connection with much smaller equipment such as may be employed within buildings for sweeping floors.

Although I have shown particular embodiments of my invention it will, of course, be understood that I do not wish to be limited thereto, since many other modifications may be made, and I therefore contemplate by the appended claims to cover all such modifications as fall within the true spirit and scope of my invention.

I claim as my invention:

1. In a power driven street sweeping apparatus including a brush for sweeping up dirt, debris, and the like, close to a surface being swept and a prime mover for actuating said brush, a dirt storage box with an open end arranged in the rear of, adjacent, and facing directly the discharge side of the brush and into which dirt is swept directly from and by said brush, said box being tiltable and having scoop means at said open end in which particles of said dirt and debris may accumulate, and means intermittently operable by said prime mover to tilt said scoop means rearwardly to flip any accumulated dirt thereon directly into and toward the back of the box.

2. In a power driven street sweeping apparatus including a brush for sweeping up dirt, debris, and the like, close to a surface being swept and a prime mover for actuating said brush, a dirt storage box with an open end arranged in the rear of, adjacent, and facing directly the discharge side of the brush and into which dirt is swept directly from and by said brush, said box being tiltable and having scoop means at said open end in which particles of said dirt and debris may accumulate, and means intermittently operable by said prime mover to tilt said scoop means rearwardly to flip any accumulated dirt thereon directly into and toward the back of the box, said scoop means comprising a pickup plate pivotally supported at the forward edge of said box and tiltable without requiring tilting of said box.

3. In a power driven street sweeping apparatus including a brush for sweeping up dirt, debris, and the like, close to a surface being swept and a prime mover for actuating said brush, a dirt storage box with an open end arranged in the rear of, adjacent, and facing directly the discharge side of the brush and into which dirt is swept directly from and by said brush, said box having scoop means at said open end in which particles of said dirt and debris may accumulate, and means operable by said prime mover to tilt said scoop means rearwardly to flip any accumulated dirt thereon directly into and toward the back of the box, said scoop means comprising an integral downwardly curved lip on the forward lower edge of said box, and said tilting means being connected to an intermediate portion of said box to effect a tilting of said scoop means through the rearward tilting of the entire box.

4. In a power driven street sweeping apparatus including a brush for sweeping up dirt, debris, and the like, close to a surface being swept and a prime mover for actuating said brush, a dirt storage box with an open end arranged in the

rear of, adjacent, and facing directly the discharge side of the brush and into which dirt is swept directly from and by said brush, said box being tiltable and having scoop means tiltable by said prime mover and disposed at said open end and in which particles of said dirt and debris may accumulate, and means operatively connected to said prime mover for tilting said box and for intermittently tilting said scoop means rearwardly to flip any accumulated dirt thereon directly into and toward the back of the box, said means including a pivoted support for the box disposed between the ends of the box.

5. In a power driven street sweeping apparatus including a brush for sweeping up dirt, debris, and the like, close to a surface being swept and a prime mover for actuating said brush, a dirt storage box with an open end arranged in the rear of, adjacent, and facing directly the discharge side of the brush and into which dirt is swept directly from and by said brush, said box being tiltable and having scoop means at said open end in which particles of dirt and debris may accumulate, means intermittently operable by said prime mover to tilt said scoop means rearwardly to flip any accumulated dirt thereon directly into and toward the back of the box, and means for tiltably supporting said box whereby the rear end of said box may be tilted down-

wardly, and said box having a movable closure at its rear end arranged to be opened when it is desired to empty the tilted box.

6. In a power driven street sweeping apparatus including a brush for sweeping up dirt, debris, and the like, close to a surface being swept and a prime mover for actuating said brush, a dirt storage box with an open end arranged in the rear of, adjacent, and facing directly the discharge side of the brush and into which dirt is swept directly from and by said brush, said box being tiltable and having scoop means at said open end in which particles of dirt and debris may accumulate, means intermittently operable by said prime mover to tilt said scoop means rearwardly to flip any accumulated dirt thereon directly into and toward the back of the box, and means for tiltably supporting said box whereby the rear end of said box may be tilted downwardly, and said box having a movable closure at its rear end arranged to be opened when it is desired to empty the tilted box, said intermittently operable means including a cam mounted on said box supporting means and being arranged to tilt said scoop means without tilting said box.

RONALD CLEMENT EVANS.
